UNITED STATES PATENT OFFICE.

HANS HONIGMANN, OF DULUTH, MINNESOTA.

AUTOMATIC FEEDING DEVICE FOR PLATEN PRINTING-PRESSES.

1,174,724.

Specification of Letters Patent. Patented Mar. 7, 1916.

Application filed April 7, 1914. Serial No. 830,180.

To all whom it may concern:

Be it known that I, HANS HONIGMANN, a citizen of the United States, residing at Duluth, in the county of St. Louis and State of Minnesota, have invented certain new and useful Improvements in Automatic Feeding Devices for Platen Printing-PresSES, of which the following is a specification, reference being had therein to the accompanying drawing.

My invention relates to improvements in automatic feeding devices for platen printing presses.

The object of my invention is to provide an automatic feeding device connected to and operated by the press, in which the sheets of paper are fed from the stack and carried to the press, and in which the previously printed sheet is simultaneously removed and stacked in another place upon each operation of the platen of the press.

Another object of my invention is to provide a stacker of this character so constructed and arranged that the swinging or moving thereof into operative position couples the working part thereof with a necessary working part of the press for operating the feeder, whereby the feeder can be readily thrown into or out of operation and when so desired the press can be fed by hand.

A still further object of my invention is to provide a feeder of this character which is simple in construction and effective in operation and needs no attention after set in operation except to place the stack of paper to be printed upon.

In the accompanying drawings: Figure 1 of the drawings is a top plan view of my improved feeder, illustrating in detail only those parts essential to my present invention. Fig. 2 is a front elevation of Fig. 1, looking in the direction of the arrow. Fig. 3 is a sectional view through the feeder and illustrating its relative position to the platen of the press. Fig. 4 is a top plan view of the stock apron, showing the adjustable side gage plates. Fig. 5 is a side elevation of Fig. 4. Fig. 6 is a vertical central section of the fore end of one of the side wings of the stock apron. Fig. 7 is a horizontal cross-section of Fig. 6. Fig. 8 is a sectional view partly broken away and illustrating the pneumatic sheet manipulating means. Fig. 9 is a perspective view of my improved reciprocating member showing the sheet en-

gaging member. Fig. 10 is an enlarged side elevation of the sheet accelerating means, with a portion of the stock apron in section. Fig. 11 is a side elevation of the air pump connection.

Referring now to the drawings, 1 represents the pivotal center upon which the feeder frame is mounted. This pivotal center is carried by an ear 1' and is adapted to rest upon an outwardly extending ear carried by the frame of the platen printing press and so arranged that it can be swung around so as to bring the feeder into operative connection with the printing press and at the same time so position it that it will feed the sheets of paper from the stack to the platen of the press, as will be hereinafter more fully described. The feeder frame 2' consists of side-walls 2 and 3 and cross-bars 4, 5, and 6, and is mounted adjacent the platen 7 of a printing press, such as is described and shown in my Patents Numbers 970,822 and 1,074,720.

The sheet manipulating mechanism, which will be hereinafter more fully described and mounted within the feeder frame 2' is operated in unison with the operation of the press in any desired manner, preferably through the medium of suitable gear wheels 8 and 9, which are mounted upon the main shaft 10 of the feeder, and which shaft is continuously rotated when the feeder is in operation. The shaft 10 being operated by the press is timed with the platen 7, whereby the feeding mechanism is adapted to operate at the proper time to remove the printed sheet from the platen and simultaneously place another sheet in position thereon to be printed.

The shaft 10 is rotatably mounted within the walls 2 and 3 and extends across the feeder frame and adjacent the wall 2 has fixed thereupon the cam 13 engaging a roller 14 mounted within the upper end of a pitman 15, and which engagement during the rotation of the cam through the medium of the shaft transmits a reciprocating motion to said pitman. The said pitman at its lower end has the laterally projecting member 16 which bears up against the free end of a crank arm 17, pivotally mounted upon the shaft 18 and carrying the rocker shaft 19. There are two of these crank arms 17, one upon each end of the shaft 18. However, the one shown in Fig. 3 of the

drawing as being actuated by the reciprocating pitman 15 imparts a like movement to the one at the opposite end of the shaft 18 through the medium of the rocker shaft 5 19 being fixed thereto.

The pitmen 20 are pivotally attached, one to the free end of each crank arm 17 and extend upwardly and vertically supported by suitable loose connections 21—21 carried 10 by the oscillating shaft 22, mounted therein and which shaft 22 is further supported by means of sliding rods 23—23 which reciprocate vertically within the guides 24—24 carried by the shaft 25, rigidly supported between the side walls 2 and 3 of the feeder frame and extending across the same. By 15 this structure it is seen that the shaft 22 with its various attachments will remain normally at the lowermost extremity of its stroke and, to assist such downward tendency, a spring 26 may be utilized which would exert inward draft upon the crank arms 17, as clearly shown in Fig. 8.

The shaft 10, adjacent the side wall 3 of 25 the feeder frame has fixed thereon a second cam 27 engaging with and actuating the roller 28 carried by the free end of the crank-arm 29 which is rigidly fixed to the shaft 22 and whereby the said crank arm is oscillated through the power imparted by the undulating shape of the cam 27, this shape being such as to impart the proper motion to the crank arm 29 at the proper time to be in step with the other working parts of 30 the mechanism, as will be hereinafter more fully described. Slidably and adjustably fixed on the shaft 22 on the inside of the arms 29, are the hubs 31, in which are adjustably mounted the downwardly extending 35 rods 30 having at their lower ends the adjustable suction cups 32. These cups are adjustable in that they are offset laterally somewhat from the ends of the rods 30, by means of the arms 33, and which arms are 40 screw-threaded upon the ends of the rods 30 and radially adjustable thereon. The arms 33 are hollow and communicate with the suction cups 32 at their outer ends and their inner ends are provided with a nipple 34, 45 upon which is placed the air suction tubes 35, which lead from the suction pump 35. The construction and operation of this pump will be hereinafter more fully described. By this structure it will be seen that when 50 the suction is caused or developed in the pump 35, there will be a suction in the tubes 35 and also in the arms 33 and cup 32, whereby when the cups engage the uppermost sheet of the stack of paper, it will 55 pick the same up and convey it therewith to the proper place, which will be later described.

The stock apron or shelf 36 is removably supported within the feeder frame and has its 60 forward edge abutting the rear edge of the

cross-bar 5 and inclined to properly feed the sheets downwardly toward the rear wall of the bar 5, as clearly shown in Figs. 3, 70 and 10 of the drawings. The stock apron or shelf 36 is provided with side wings 37 70 mounted upon a cross-rod 38, carried by the brackets 39 at the sides of the apron 36. By this structure it will be seen that the wings 37 may be moved inwardly or outwardly to engage the edges of the stock of paper for 75 receiving sheets of paper of different sizes. The forward end of each side wing is provided with an extension 40, having a hollow chamber 41 therein terminating externally at its rear end into the elongated nipple 42, 80 upon which is placed an air-supply pipe 43 and through which a blast of air passes, as will be presently described. The forward or outer end of the hollow chamber 41 is provided with a vertically lateral slot 44 85 through which the blast of air passes to the edge of the stock-pile carried by the apron 36 for the purpose of slightly lifting or freeing the uppermost sheet from the pile when it is first lifted therefrom and avoid 90 the attraction of the second sheet. The extension 40, in its inner face in rear of the vertical slot 44, is provided with a vertically disposed concave recess 45, to permit the escape of any super-confined air which may 95 be forced intermediate the sheets and also to prevent the air-blast from unduly exercising the sheets. These recesses also admit of a partial release of adhesive force when it becomes necessary to place the suction 100 cups in a position overlapping the edges of the stock pile and slightly projecting within such recesses. In order to still further prevent any possibility of the disarrangement of the sheets, I provide the extension 40 of the apron 36 with the inwardly turned lips 46 carried by an annular nose-piece 47, which is adjustably connected to the extension 40 by means of the thumb screw, and which lip 46 forms a stop 105 to any sudden upward movement of the top sheet and which stop is readily overcome when the sheet is being lifted by the suction cups heretofore described.

A sheet accelerating device is provided 115 and this is in the form of a resilient roller 50, mounted upon the center of the shaft 18. This shaft 18 is intermittently rotated by the action of the pawl 51 engaging the ratchet 52, formed upon the periphery of 120 the shaft 18. The pawl 51 is pivotally supported at 53 within the free bifurcated end 54 of the crank arm 55. This crank arm 55 is loosely mounted upon the shaft 56 and the opposite end 57 of the crank-arm carries 125 a roller 58, which engages the cam 59 rigidly fixed upon the shaft 10, and said cam 59 being timed with the running mechanism so that the friction roller 50 is rotated at the proper time. The rotation of the shaft 18 130

and roller 50, heretofore described, by the pawl 51 is comparatively short. This short rotation of the roller answers the purpose of advancing the sheet sufficiently for it to be grasped by the reciprocating means, before the further rotation of the shaft and roller through the medium of the spur-wheel 60, advances the rack. The spur-gear 60 is fixed to a disk 61 loosely mounted upon the shaft 18 adjacent the ratchet and which gear carries the bar 62, which carries the reciprocating members, the construction of which is old and needs no further description. The motion from the disk 61 is imparted to the shaft 18, by means of a plurality of small pawls 63 pivoted upon the disk 61 and which engages the ratchet 52 adjacent the pawl 51. By this structure it will be seen that the pawl 51 may revolve the shaft 18 independent of the disk 61 and vice versa, whereby the roller 50 may be set in motion to start the sheet, as heretofore described. A second roller 64 is mounted upon a suitable arm 65, which is lowered below the stock apron and is constructed and arranged to intermittently bear upwardly at the proper time against the roller 50, so that the said roller will engage or come in contact with the sheet. In order to check or retard the motion of the sheet as it leaves the extension 40 of the apron 36, I have provided a member 66, which has its outer ends 66' turned upwardly, as clearly shown in Fig. 10 of the drawings. These ends, as shown, are on either side of the roller 64, the members 66 are rigidly attached to the cross-shaft 67 and carried by said shaft is a crank arm 68 connected at 69 to the vertically disposed pitman 70. The upper end of the pitman 70 is provided with a roller 71, which engages and derives its power from a cam 72, fixed upon the shaft 10. This cam is so shaped and arranged upon the shaft 10 as to depress the member 66 at the proper time for the sheet delivery. The members 66 are normally held in an upward position by means of a suitable spring 73 intermediately attached to the radial arm of the crank 68, and the opposite end of the spring connected to the bar 4 of the feeder frame. By this structure it will be seen that the member 66 is normally held in its upward position to retard the sheet as it leaves the member 5, but is depressed at the proper time by the cam 72 to allow the sheet to pass.

The reciprocating sheet conveying member 74, consists of an elongated member pivoted at its rear end to the rack 62 and whereby the reciprocation of the rack, heretofore described, will cause the sheet conveying member to reciprocate for removing the printed sheets from the platen 7 to the conveyer 12, from which they are discharged upon the stack, not shown, in rear of the said conveyer. The outer end of the recip-

rocating member 74 is provided with a bow-shaped gripping member 75 fixed to the shaft 76, which in turn is rotatably mounted within the offset finger 77 of the reciprocating member. This shaft 76 also carries a downwardly depending finger 78, designed when not engaging the face of the platen to slightly rock the shaft 76 and thereby lift the knuckle 79 of the bow-shaped gripping member 75 from engagement with the reciprocating sheet conveying member 74, as clearly shown in Fig. 9 of the drawing. Releasing by contact with the platen only occurs as the sheet is about leaving the reciprocating elements and turning their backward stroke, at the extreme end of which the engagement must again be broken and this is accomplished by the rod 80 radially carried by the rocker shaft 19 and adapted to engage the upper portion 81 of the member 75, and thereby tipping up or raising the knuckle 79 from contact with the finger 75 for the reciprocation of the incoming sheet. A spiral spring 82 is wound about the shaft 76 and attached in such a manner as to keep the gripping member 75 normally in contact with the reciprocating member 74 and to insure of the firm holding of the sheet when thus engaged.

In order to cause a suction for the suction cups 32 and also an air-blast for the member 40, heretofore described, I have provided a rotating shaft 85 having mounted thereon a disk 85 provided with a wrist-pin and to which is pivotally connected the pitman 84. Below the pitman 84 is a pump 35 pivotally connected at 86 to a stationary part of the printing press frame 87 and which is adapted to furnish the necessary air required in the operation of the feeder. Connected at the upper and lower ends of said pump are the two pipes 88 and 89, which, as heretofore stated, lead to the connections 35 of the suction-cups and also to the connections 43 of the stock table and which needs no further description.

The operation of my device is as follows: The feeder is normally held out of operation with the press, whereby the press may be fed by hand if desired. When it is desired to use the improved feeder, the same is swung inwardly toward the press upon the pivot so that the gear wheels engage the gear carried by the press and the gears so timed with the operation of the platen 7 of the press, that a previously printed sheet is removed from the platen by the reciprocating member 74 and a second sheet simultaneously fed to the platen, which I will now proceed to describe. The stock is piled upon the apron 36, as heretofore described, and the guides 37 are moved inwardly so as to hold the stock against lateral movement. The starting of the press causes the shaft 10 to be set in operation, which in turn starts the racks 62

outwardly so as to move the reciprocating sheet conveying member outwardly over the platen 7 of the press to remove the previously printed sheet inwardly by the member 83, shown in Fig. 9 of the drawings. Simultaneously with the operation of this outward movement of the reciprocating sheet conveying member 74, the suction cups 32 move down upon the top sheet of the pile 10 or stock and is slightly raised, lifting with it the top sheet from the pile. Simultaneously with this operation a blast of air is forced through the pipe 43, which aids in lifting the top sheet from the pile of the stock. Simultaneously with this movement the cam 27 allows the arm 29 to swing downwardly which swings the suction cups 32 outwardly and conveys the top sheet of the stock outwardly upon the member 5. Simultaneously with this movement the continuously operated shaft 10 has brought the cam 37 into a position to force the intermediate pivoted lever 54 upwardly so that the pivoted rack 51 is forced forward engaging the ratchet wheel 52 on the shaft 18, and causing a partial rotation of the shaft and the roller 50 carried by the shaft 18 will make a partial rotation, engaging the sheet still being held by the suction cups 32 and deliver the sheet to the reciprocating member 74, which conveys the sheet to the platen of the press. The stop 66 having been depressed through the medium of the crank 68, the pitman 70 and cam 72 allow the sheet to pass from the member 5.

Having thus described my invention, what I claim and desire to secure by Letters Patent is:

1. The combination with a platen printing press, of a frame pivoted thereto, of a reciprocating feeding member adapted to convey the sheets of paper to and from the platen of the press, an oscillating suction means adapted to raise the top sheet of the stock and convey it to a point adjacent the feeding member, and a roller for receiving the sheet from the suction means and delivering it to the reciprocating feeding member, and means operated by the press and continuously driven, for operating the suction member, the roller and the feeding member in their proper order.

2. The combination with a platen printing press, of a frame adjacent thereto, a reciprocating feeding member adapted to convey the sheets to and from the platen of the press, an oscillating suction means adapted to convey the sheets from the stock to a point adjacent the feeding member, a roller adapted to receive the sheet from the suction means and deliver it to the reciprocating feeding member, and an air-blast for aiding in lifting the top sheet from the stock, and means operated by the press for operating the air-blast, the suction member, roller and the re-

ciprocating feeding member in their proper order.

3. The combination with a platen printing press, of a frame adjacent thereto, a stock supporting shelf carried by the frame and having adjustable side guide-plates, an oscillating suction means for lifting the top sheet of the stock, means carried by the adjustable guide-plate for allowing an air-blast to aid in raising the top sheet of the stock, said suction means adapted to convey the sheet to a point adjacent the feeding member, an intermittently driven roller adapted to receive the sheet from the suction means and convey it to the feeding member, and means operated by the press for operating the several parts in their proper order.

4. The combination with a platen printing press, of a pivoted frame adapted to be swung into operative position with the press, a stock support carried by the frame, adjustable side guide-plates carried by the support and having means for causing a blast of air at the side of the stock, an oscillating suction means adapted to engage and lift the top sheet of the stock and convey it to a point adjacent the reciprocating feeding member, a stop for limiting the movement of the sheet, a roller for engaging the sheet while being held by the suction means and conveying it to the reciprocating feeding member, and means operated by the press for operating the several parts in their proper order.

5. The combination with a platen printing press, of a frame pivoted thereto and adapted to be swung around into operative position, a shaft carried by the frame, a gear carried by the shaft and meshing with a continuously rotated gear on the press, a reciprocating feeding member carried by the frame and adapted to convey the sheets to and from the platen of the press, an oscillating suction member carried by the frame and operated by the shaft for raising the top sheet of the stock and conveying it to a point adjacent the reciprocating feeding member, an intermittently driven roller adapted to receive the sheet from the reciprocating suction member and conveying it to the reciprocating feeding member, substantially as shown and described.

6. The combination with a platen printing press, of a frame pivoted adjacent thereto and adapted to be swung into or out of operative position with the press, a shaft carried by the frame, a gear carried by the shaft and meshing with a continuously rotating gear on the press, an oscillating suction means adapted to lift the top sheet of the stock and convey it to a point adjacent the oscillating feeding member, an air-blast for aiding in lifting the top sheet of the stock, and an intermittently driven roller

adapted to receive the sheet from the suction means and convey it to the reciprocating feeding member.

7. The combination with a platen printing press, of a frame pivoted adjacent thereto and adapted to be swung around into operative position, a horizontal shaft carried by the frame, a gear carried by the shaft and meshing with a continuously rotating gear carried by the shaft, a stock support carried by the frame, adjustable side-guide plates carried by the support, means for causing a blast of air from the side plates in a horizontal direction, an oscillating suction means

15 for engaging the top sheet of the stock and conveying it forwardly, a rotary roller adapted to engage the sheet while being held by the suction means and an oscillating and reciprocating feeding member adapted to receive the sheet from the roller and conveying it to the platen of the press.

8. The combination with a platen printing press, of a frame pivoted to the press and adapted to swing in or out of operative position therewith, a gear carried by the frame and meshing with a continuously driven gear of the press, a reciprocating feeding member operated by the gear, an oscillating suction means adapted to lift the top sheet of the stock and convey it to a point adjacent the feeding mechanism, and an intermittently driven roller adapted to engage the sheet while being held by the suction means and delivering it to the reciprocating feeding member.

9. The combination with a platen printing press, of a frame pivoted to the press and adapted to be swung in or out of operative position with the press, an oscillating reciprocating feeding member carried by the frame, a gear carried by the frame meshing with a continuously rotating gear carried by the press, means carried by the gear for oscillating and reciprocating the feeding member, a stock support carried by the frame, adjustable side guide-plates carried by the support, means operated by the gear

for causing a blast of air from said side plates, an oscillating suction member adapted to engage the top sheet of the stock simultaneously with the blast of air and conveying the sheet to a point adjacent the reciprocating feeding member, an intermittently driven roller adapted to engage the sheet while being held by the suction member, a stop adapted to limit the movement of the sheet, means operated by the gear for moving the stop downwardly and means operated by the gear for rotating the roller for feeding the sheet to the oscillating reciprocating feeding member.

10. A feeding device for printing presses, comprising a frame, an oscillating and reciprocating feeding member carried by the frame, an air-blast and suction means simultaneously operating upon the top sheet of the stock and conveying said sheet toward the reciprocating feeding member, a roller carried by the frame and adapted to operate upon the sheet while being held by the suction means and delivering it to the feeding member, and means carried by the frame for operating the air-blast, the suction means and roller and the reciprocating feeding member in their proper order.

11. A feeding device for a printing press, comprising a frame, a reciprocating feeding member carried by the frame, a stock support carried by the frame, air blast means and suction means for lifting the sheets from the stock pile support and conveying same to the reciprocating feeding members, means within the stock support whereby the suction means may overlap the edges of the stock pile when in engagement therewith and a roller adapted to convey the sheet from the suction means to the reciprocating feeding members.

In testimony whereof I hereunto affix my signature in the presence of two witnesses. 90
